[57] **CLAIM**

The ornamental design for an enclosure for circuit protection related devices, as shown and described.

DESCRIPTION

FIG. 1 is an upper, front, right perspective view of an enclosure for circuit protection related devices showing our new design;

FIG. 2 is an upper front, left perspective view thereof;

FIG. 3 is a left side elevational view thereof;

FIG. 4 is a top plan view thereof;

FIG. 5 is a front elevational view thereof;

FIG. 6 is a right side elevational view thereof;

FIG. 7 is a bottom plan view thereof.
